DESIGN FOR AN ILLUMINATED MIRROR

Edwin W. North, Rockford, Ill., assignor to National Lock Co., Rockford, Ill., a corporation of Delaware

Application June 27, 1934, Serial No. 52,353

Term of patent 7 years

To all whom it may concern:

Be it known that I, Edwin W. North, a citizen of the United States, residing at Rockford, in the county of Winnebago and State of Illinois, have invented a new, original, and ornamental Design for an Illuminated Mirror, of which the following is a specification, reference being had to the accompanying drawing, forming part thereof.

In the drawing:

Fig. 1 is a side view;
Fig. 2 is a front view; and
Fig. 3 is a rear view.

I claim:

The ornamental design for an illuminated mirror, as shown.

EDWIN W. NORTH.
